UNITED STATES PATENT OFFICE

2,454,934

ELECTRICAL OXYGEN VAPORIZER AND
PROTECTING COVERJohn A. Mathis and Roland W. Milan,
Pinckneyville, Ill.

Application January 24, 1947, Serial No. 724,202

9 Claims. (Cl. 62—1)

1

This invention relates to apparatus for converting liquified gases and particularly oxygen into gaseous form at a controlled rate, and is an improvement upon the constructions shown in our two previously granted Patents Nos. 2,158,458 issued May 16, 1939, and 2,401,651 issued June 4, 1946.

One object of the present invention is to provide an improved construction for a container of the spaced wall, evacuated type for liquified gas that is much safer to use than the prior known containers and which will not inflict injury upon personnel or cause property damage in the event of a rupture of the inner wall of the container.

Another object is to provide an improved arrangement for automatically increasing the rate at which the liquid oxygen is normally converted to its gaseous form to satisfy temporary peak demands for the oxygen.

Another object is to provide for selectively delivering the gas at either its normal rate as determined by the heating capacity of the electric heater unit or at a much higher rate.

Yet another object is an improved arrangement of an electrical heater element and thermostat in a double walled vessel of the Dewar flask type used for dispensing a liquified gas in vapor form.

A more specific object of the invention is to provide an improved Dewar flask type oxygen converter that includes a valve controlled liquid inlet, a valve controlled gas outlet and a valve controlled connection between the inlet and outlet for admitting liquid oxygen directly into the gas outlet so that the volume of gas normally generated by heating the liquid within the flask may be augmented when necessary by direct evaporation of the liquid from the inlet.

These and other objects and advantages derived from the invention will become more apparent from the following detailed description when considered with the accompanying drawings in which:

Fig. 1 is a front elevation of the apparatus;

Fig. 2 is a central, vertical section of the apparatus;

Fig. 3 is a diagram of the gas-valve electrical system;

Fig. 4 is a horizontal section taken on line 4—4 of Fig. 2;

Fig. 5 is a horizontal section taken on line 5—5 of Fig. 2;

Fig. 6 is a detail vertical section taken on line 6—6 of Fig. 2, parts being shown in elevation;

Fig. 7 is a fractional horizontal section taken on line 7—7 of Fig. 2;

2

Fig. 8 is a plan view of the liquid level indicator:

Fig. 9 is a vertical section taken on line 9—9 of Fig. 8, a part of the dial being broken away; and

Fig. 10 is a detail vertical section taken on line 10—10 of Fig. 2.

Referring now to the drawings, the improved oxygen converter is a generally spherical flask comprising inner and outer concentric hollow spheres 1 and 2, the space between the two spheres being evacuated in the usual manner to prevent the transfer of heat between the surrounding air and the inner sphere 1. Both spheres may be made up from hemi-spherical members preferably of stainless steel joined together. Each of the spheres has a neck portion (1a and 2a) and the space between the two necks is sealed with an annular disc 3. The inner neck 1a is closed at the top by a cap member 4 containing a number of passageways. One passageway 5 that extends partially through the cap in an axial direction and then turns horizontally is provided for filling the sphere 1 with liquid oxygen.

10 The outer end of this passageway is threaded for receiving a pipe stub 6 to which is connected a T nipple 7, and a stub conduit 8 and a manually actuated filling or inlet valve 9 are connected to the nipple 7. The inner end of passageway 5 is 15 extended nearly to the bottom of the inner sphere by means of an inserted tube 12. The flask is filled with liquid oxygen by coupling a supply pipe 13 to the inlet side of the valve 9 and opening a gas exhaust valve which will be described later. The neck portion 1a of the inner vessel 20 extends downwardly into the main body portion for a distance sufficient to prevent overfilling with liquid oxygen, the distance depending upon the amount of working pressure to be used. Liquid oxygen expands rapidly upon being 25 warmed so that its density changes from 72 lbs. per cu. ft. at sea level pressure to approximately 64 lbs. per cu. ft. at 100 lbs. pressure. This expansion of the liquid itself is capable of producing an increased pressure which is not dependent 30 upon the temperature of the liquid and has proven troublesome in the past when the converters were overfilled. By so extending the neck portion 1a, overfilling is prevented and a small 35 space is left at the top of the container into which the liquid oxygen cannot be introduced.

Another passageway 14 in the cap 4 opens into the neck 1a and the outer end of this passageway is also threaded for receiving a stub conduit 15 40 onto which is threaded a four-way nipple 16. 45

Branching off from the nipple 16 is a safety valve 17 which is pressure responsive and opens in the event that the pressure of the gas rises to a danger point, a conduit 18 leading to a pressure responsive switch that will be explained later in more detail, a manually actuated outlet valve 19, and a manually operated gas release valve 20.

A third passageway 21 through the cap 4 is provided for a rod 22 of a liquid level indicating device comprising a float 23 having an arm 24 connected by means of a U clamp 25 to a shaft 26 on which is fixed a pinion gear 27 that meshes with a gear 28 secured to the lower end of rod 22. The shaft 26 is journalled at one end of a bracket 29, the other end of this bracket being fastened to the inner surface of the inner hollow sphere. The upper end of rod 22 enters a liquid level gauge 30 that is shown particularly well in Figs. 8 and 9 supported upon cap 4. The gauge includes a graduated scale 31 swept by a pointer 32 that is rotated by the rod 22 as the latter rotates with the rise and fall of float 23 with changes in the level of the liquid oxygen.

Surrounding the outer shell 2 and serving as a support for the oxygen converter are a pair of dished cap members 35, 36 having rim portions 37, 38. These rims are provided with two series of apertures 39, 40 spaced evenly around them. The apertures 39 in the top and bottom cap members 35, 36 are aligned to receive spacing bolts 41 which secure the caps snugly on the outer shell 2. A multiple strand cable 42 having a very high tensile strength such as used for the control cables of aircraft is woven back and forth through the other series of apertures 40 in the two cap members in an interlacing manner and serves as a safety device for protecting personnel from bodily harm in the event of accidental rupture of the inner vessel 1. Should the latter break, and liquid oxygen leak out into the otherwise evacuated space between the inner and outer containers 1 and 2, the oxygen would of course be converted into vapor at a high rate due to the fact that the wall of the outer container 2 is at ambient temperature as compared with a temperature of -183° C. for the liquid oxygen and thus might result in an explosion of the outer container. The interlaced metal cap members 35, 36 strengthen the outer container 2 and reduce the possibility of bursting. However should the latter take place, the cap members 35, 36 will serve to prevent the vessel from flying apart as the wire cable 42 is made strong enough to hold the caps together regardless of what happens to the oxygen vessel.

The spacer bolts 41 also help in a limited degree to reduce the explosion effect of the outer container 2 but these cannot be relied upon to any great extent because the rims 37, 38 have been found to tear at the bolt holes.

As an extra safeguard against bursting of the apparatus, a plurality of small holes 33 may be drilled through an exposed portion of the wall of the outer vessel and these sealed with a soldered cover plate 34 of copper designed to give way at a pressure of approximately 75 lbs./sq. in.

The bottom cap member 36 is fixed to a dished support 44 that serves as a floor stand for the oxygen converter.

A bracket 45 made from strap material that is bolted to the upper cap member 35 serves as a support for a warming coil 46 which is connected to the outlet side of the gas outlet valve 19 and also supports a pressure responsive switch 47 and a relay 48. As shown in Fig. 3, the pressure responsive switch 47 includes a fixed contact 49

and movable contact 50, the latter being actuated by armature 51 linked to a bellows 52 to which the conduit 18 is connected. The latter as previously explained is connected to the four way nipple 16 and hence bellows 52 is actuated in response to the pressure of the gaseous oxygen at the outlet side of the converter.

A short conduit 53 extends from the T nipple 7 in the liquid inlet line to a nipple 54 which is placed in the gas outlet line between the outlet valve 19 and the entrance to warming coil 46. A manually adjustable needle valve 55 is placed in conduit 53 and as will later be explained can be used to admit liquid oxygen directly into the warming coil 46 when it is desired to increase the normal rate of flow of gaseous oxygen from the converter. An additional manually controlled valve 60 may be connected at the exit of the warming coil 46.

When the converter is initially filled, the liquid oxygen 56 is at an approximate temperature of -183° C. and at atmospheric pressure, under which conditions it is substantially in equilibrium. The liquid is converted to vapor form by the application of heat which is derived from an electrical heater unit 57 of the resistance type which is enclosed within a copper jacket 58. The lower end of the latter is reduced, passed through the wall of the inner vessel 1 and there connected to the lower end of a metal conduit 59 preferably of Monel, a nickel copper alloy. The reduced portion of jacket 58 can be spot welded to the inner vessel at the point where it passes through the vessel wall to anchor it in place.

Mounted beside the heater unit 57 is a thermostat 61 comprising a pair of bimetallic leave type contacts 62, 63 which are normally closed as shown in Fig. 2 of the drawing. The thermostat is also housed within a metal jacket 64 that is connected by a metal strap 65 to jacket 58 so that the heater unit 57 and thermostat 61 will be in good heat transfer relationship. The thermostat jacket 64 also has a reduced end passed through and welded to the wall of the inner vessel that connects to a Monel conduit 66.

The two conduits 59 and 66 extend upwardly in the evacuated space between the inner and outer vessels 1, 2 and on opposite sides thereof, and emerge through openings 67 and 68 provided near the top of the outer vessel 2 and the upper cap 35. The openings 67 in the outer vessel 2 are of course sealed around the conduits 59, 66 so that the vacuum between the vessels is not disturbed. Furthermore, it will be evident that by extending the Monel conduits 59, 66 nearly up to the neck of the outer vessel before bringing them out through the vessel wall, a long and low conductivity heat path is provided which minimizes any heat transfer that may take place from the air surrounding the converter apparatus (usually at ambient temperature) to the liquid oxygen by conduction through the walls of the conduits 59, 66 and the walls of jackets 58 and 64.

Referring now to Fig. 3, the relay 48 is seen to be of the electromagnetic type and includes a coil 69, an armature 70 carrying contact 71 biased away from the coil core 72 by spring 73 and a stationary contact member 74.

The various circuit connections linking the electric heater element, the thermostat, the pressure switch and the relay include; a lead 75 between a terminal 76 (to which the positive side of a power supply line is connected) and the movable contact 71 of relay 48; a conductor 77 connecting the stationary relay contact 74 to one

terminal on the oxygen heater resistor 57 through a fuse 78; a lead 79 extending from one side of the relay coil 69 to contact 62 of the thermostat 61; a conductor 81 connecting the other thermostat contact 63 with the movable contact 50 on the pressure switch 47; and a lead 82 extending between the stationary contact 49 of the pressure switch to the power input terminal 76. The other terminal of the relay coil 69 is grounded as are also the other terminal of the resistor unit 57 and the other terminal 83 of the power supply line. The "ground" connections may be made through the metal parts of the converter apparatus such as the jacket 58 and the relay housing and these connections are indicated by the usual symbol on the drawing.

Operation

The improved oxygen converter operates in the following manner: Referring now to Fig. 3 the converter is first filled with liquid oxygen through the inlet valve 9. During the filling phase, the gas discharge valve 20 is opened to allow the escape of gas produced by the initial evaporation which is usually quite high at first since the evacuated container is usually warm. After the inner vessel 1 has been filled to the lower end of the neck 1a, the valves 9 and 20 are enclosed.

Referring now to the electrical circuit shown in Fig. 3, it will be seen that at this time, contacts 49, 50 of the pressure switch 47 are closed, as are also the contacts 62, 63 of the thermostat 61. Hence as soon as power is applied to the terminal 76 on the relay housing, a circuit will be completed through the contacts of the pressure switch and thermostat to energize the relay coil 69 thus closing relay contacts 71, 74 and completing the circuit for energizing the electrical heater element 57. Assuming for the present that valve 55 be closed and gas outlet valve 19 set to a desired opening, the oxygen will begin to vaporize and pass out through valve 19 into the warming coil 46 as soon as it has been sufficiently heated by the resistance element 57. Warming coil 46 is especially needed where the apparatus is used to dispense oxygen to a patient in an oxygen tent since its temperature must obviously be raised somewhat if it is to be breathed by the patient without discomfort.

The current will continue to flow through the heater element 57 until the body of liquid oxygen attains a temperature to establish equilibrium for a vapor pressure equal to the pressure at which the pressure switch is set to operate. At this point the bellows 52 will have expanded sufficiently to cause the contacts 49 and 50 to be separated whereupon the coil 69 of relay 48 is deenergized and relay contacts 71, 74 are then broken to interrupt the energizing circuit for the heater 57. When the vapor pressure drops, the contacts of the pressure switch and relay are reclosed and the heater element 57 is reenergized. Thus so long as the apparatus is connected to the line, the oxygen will be converted at a controlled rate as determined by the setting of the gas outlet valve 19 and the wattage or heating capacity of resistor 57.

The thermostat 61 functions as a safety device. As long as there is a sufficient amount of liquid oxygen within the vessel 1, most of the heat generated by the heater 57 will be absorbed by the liquid and hence the bimetallic leaf contacts 62, 63 will remain closed. However, when the level of the oxygen falls nearly to the bottom of the inner vessel 1, more of the heat from heater

57 will be transferred to the bimetallic leaves 62, 63 by conduction through the copper jackets 58 and 64 and the leaves will ultimately become sufficiently heated to break the connection therebetween, thus opening the circuit to the relay coil 69 and shutting off the power to the heater unit 57.

In operating the apparatus at normal delivery rates, the valve 55 between the liquid inlet and the warming coil 46 is closed. However with this improved construction, the normal delivery rate of gaseous oxygen may be raised when necessary in either of two different manners. If it is desired to obtain a somewhat prolonged flow of gaseous oxygen at a rate greatly in excess of that normally delivered through outlet valve 19, the latter can be closed and valve 55 opened. With the valves set in these positions, and the heater element 57 energized, the liquid oxygen will be vaporized as before. However, since outlet valve 19 is now closed, none of the vaporized oxygen can pass in this direction into the warming coil 46 and the resultant increase in vapor pressure in the container above the liquid oxygen as related to the much lower pressure in the warming coil 46 will soon force liquid oxygen upwardly through the filling tube 12 until it reaches the level of the branch conduit 53. Liquid oxygen now flows past opened valve 55 and is admitted directly into the warming coil 46 where it is immediately vaporized and at a rapid rate due to the fact that the temperature of coil 46 is practically the same as that of the surrounding air. The rate at which oxygen vapor is delivered from the converter with valve 55 open and valve 19 closed exceeds by far the delivery rate established when valve 55 is closed and valve 19 opened.

If it is desired to use the converter under conditions where the demand rate for gaseous oxygen is normal and ordinarily substantially constant, but the converter is occasionally called upon to deliver gaseous oxygen at a higher rate to satisfy temporary peak demands, valve 55 can be set to its open position and valve 19 set slightly open. With the valves in these positions, the normal demand of oxygen, for example 50 liters/min., will be supplied entirely through outlet valve 19. However, should the demand for oxygen now temporarily increase, for example to 150 liters/min., the ensuing drop in pressure in warming coil 46 would then establish a pressure differential sufficient to lift liquid oxygen in the tube 12 to the level of conduit 53 and liquid oxygen would then be admitted directly into warming coil 46 for direct vaporization to thus supply the required excess above normal. When the peak demand drops off, the vapor pressure in warming coil 46 again rises and direct admission of liquid oxygen into warming coil 46 ceases.

In conclusion it will be understood that while we have shown and described a preferred embodiment of our improved oxygen converter, changes in the specific construction and arrangement of parts may be made without departing from the spirit and scope of the invention as defined in the appended claims.

The invention described herein may be manufactured and used by or for the Government of the United States of America for governmental purposes without the payment of any royalties thereon or therefor.

We claim:

1. Apparatus for dispensing liquid oxygen and the like in gaseous form comprising a heat insulated vessel, a valve controlled liquid inlet tube,

said tube extending into the lower part of said vessel, means for heating the liquid to convert it into gas, means for controlling the operation of said heating means in accordance with the gas pressure, a gas outlet, an outlet valve for controlling the flow of gas between said vessel and gas outlet, and a valve controlled conduit interconnecting said inlet tube with said gas outlet on the discharge side of said outlet valve.

2. Apparatus for dispensing liquid oxygen and the like in gaseous form comprising a heat insulated vessel, a valve controlled liquid inlet tube, said tube extending into the lower part of said vessel, means for heating the liquid to convert it into gas, means for controlling the operation of said heating means in accordance with the gas pressure, a warming coil connected to a gas outlet from said vessel, an outlet valve for controlling the flow of gas into said warming coil, and a valve controlled conduit interconnecting said inlet tube with said warming coil at the discharge side of said outlet valve.

3. Apparatus for dispensing liquid oxygen and the like in gaseous form comprising a heat insulated vessel, a tube extending into the lower part of said vessel, means for heating the liquid to convert it into a gas, means for controlling said heating means in accordance with the gas pressure, a gas outlet, a valve for controlling the flow of gas from said vessel to said outlet, a conduit connecting said tube with said gas outlet, and valve means in said conduit whereby the liquid may be pulled off from said container into said gas outlet to increase the rate at which the liquid is normally evaporated.

4. A double wall insulating vessel for liquid oxygen and the like, said vessel being of generally spherical shape, top and bottom cap members having rim portions facing one another and provided with a plurality of apertures spaced around the rims, and a reinforcing cable woven back and forth through the apertures in said rims and interlacing the cap members together.

5. A vessel as defined in claim 4 and further including a plurality of spacing bolts interconnecting the rim portions of said cap members.

6. Apparatus for dispensing liquid oxygen and the like in vapor form comprising a double walled evacuated vessel, said vessel being of generally spherical shape and provided with a neck portion, an electrical heater element and an adjacent thermostatic switch element in the lower part of said vessel, jackets enclosing said switch and heater elements, and conduits extending from said jackets through the inner vessel wall and upwardly between the inner and outer vessel

walls, said conduits passing out through the outer wall adjacent the vessel's neck.

7. Apparatus for dispensing liquid oxygen and the like in vapor form comprising a double walled evacuated vessel, said vessel being of generally spherical shape and provided with a neck portion, an electrical heater element and an adjacent thermostatic switch element in the lower part of said vessel, metallic jackets enclosing said switch and heater elements, said jackets being provided with neck portions extending through the inner wall of said vessel and sealed thereto, and a tube extending from the neck portion of each of said jackets upwardly between the vessel walls, said tubes passing out through the outer wall of said vessel near its neck and sealed thereto.

8. Apparatus for converting liquid oxygen and the like into gas comprising, a double wall insulating vessel for the liquid, said vessel being of generally spherical shape, an electrical heater element in said vessel, a thermostatic switch in said vessel adjacent said heater element, upper and lower cap members for the outer wall of said vessel, said cap members being provided with adjacent rim portions, a reinforcing cable interlacing said cap members around the rim portions thereof, a bracket upstanding from the top cap member, a warming tube connected to a gas outlet from said vessel, said tube being coiled about said bracket, gas pressure responsive switch means supported by said bracket, a relay supported by said bracket, circuit means connecting said switches for operation in series to control said relay, and circuit means for connecting said heater element through contacts on said relay to a source of power.

9. Apparatus for converting liquid oxygen and like as defined in claim 8 wherein the outer wall of said vessel is provided with a plurality of closely adjacent apertures sealed by a frangible cover plate.
